B. C. HILL,
CURTAIN FIXTURE,
APPLICATION FILED SEPT. 3, 1918.

1,296,289.

Patented Mar. 4, 1919.

UNITED STATES PATENT OFFICE.

BEULAH C. HILL, OF CHICAGO, ILLINOIS.

CURTAIN-FIXTURE.

1,296,289.

Specification of Letters Patent.

Patented Mar. 4, 1919.

Application filed September 3, 1918. Serial No. 252,299.

To all whom it may concern:

Be it known that I, BEULAH C. HILL, a citizen of the United States, residing at Chicago, in the county of Cook and State of Illinois, have invented certain new and useful Improvements in Curtain-Fixtures, of which the following is a specification.

My invention relates to devices for holding curtains by means of top and bottom rods. More specifically it relates to an adjustable member for holding one end of one of the rods.

The objects of my invention are chiefly to provide simple, low-cost and readily operable means for holding a curtain on the curtain rods so that the effective distance between the upper and lower rods may be varied, whereby curtains of different lengths may be placed upon the rods and maintained in the desired taut or stretched condition, and, importantly, whereby the curtain may be so maintained, although there be material shrinkage thereof, due to washing, and, further, whereby, after washing such curtain, it may be put upon the rods while wet and the rods then separated until the fabric is drawn taut, thus substantially "ironing" the washed curtain without the great difficulty incident to stretching the same on some auxiliary device. As to the specific construction, it is a prime object to provide a form of device of simple construction, of few parts, and one which may be readily installed; and, further, a form of device which may be used on either side of the window frame, thus avoiding the difficulty incident to the application of "rights" and "lefts", as where the devices are used in pairs. Further objects and advantages will appear hereinafter.

It is common practice to secure window curtains by means of a rod passing through a hem or turned-over portion at both the top and bottom of the curtain. Numerous advantages exist in such an arrangement over the method of suspending the curtain from a single rod at the top. Heretofore, however, such difficulties as maintaining the curtain taut under the various conditions of service and difficulties of installation, removal, etc., have limited the effectiveness and practicability of the two-rod system. These difficulties are overcome by the present improvements, and numerous advantages due to the particular form of construction illustrated are also obtained.

In the accompanying drawings, which form a part of this specification, I have illustrated two forms of the adjustable rod support, each of which is a preferred form in the use to which it is particularly adapted. In these drawings Figure 1 is a face view of a window frame, showing a two-part curtain and the curtain rods held by the devices of Figs. 2 and 6, the holding elements being enlarged proportionately and the curtain being shown as mere strips of fabric, for clearness of illustration; Fig. 2 is a face view of the fixture applicable to the inner sides of a window frame, as in Fig. 1, together with a fragment of the frame; Fig. 3 is an edge view of the device of Fig. 2; Fig. 4 is a face view of a form of the device for application to the window frame or sash surfaces which are substantially parallel with the window; Fig. 5 is an edge view of the device of Fig. 4; and Fig. 6 is a perspective of the lower rod-retaining member of Fig. 1.

Referring to Fig. 2, the structure consists of a strip of metal 10, suitably of iron or brass, stamped up to provide the projecting middle portion 11, which is notched at 12 to receive the end of the upper curtain rod 13. The device is thus provided with two legs A and B, extending from the central portion 11, and each of these legs is provided with a longitudinal slot 14 of a width sufficient to receive loosely the shank of a holding screw, and a plurality of screw-receiving slots or branches 15 extending on each side of slot 14 and turned normally upward at their ends respectively, when this member 10 is used for holding the top rod. The provision of such lateral slots or branches 15 on both sides of the central slot 14 makes the device available for use on either side of the window frame. As shown in Fig. 2, the screws 16 and 17, which may be ordinary wood-screws of commerce, preferably round-headed, are screwed into the wood frame, the two being preferably in a substantially vertical line, and are spaced apart the distance between corresponding grooves or branches 15 in the upper and lower legs of the structure 10. The construction and arrangement are such that the structure 10 may be moved up and down with the screws 16 and 17 in the longitudinal slots 14, and becomes locked against downward movement when the structure 10 is moved laterally so that the screws 16 and 17

will each be engaged by one of the grooves or branches 15 in the upper and lower legs, A and B. The structure 10 may therefore, by a simple movement of the hand, be moved 5 out of one of its locked positions and into another thereof, higher or lower, thus varying the distance between the upper and lower rods. The screws 16 and 17 are not turned into the frame so tightly as to bind 10 upon the device 10, but only so closely thereto as to maintain the device 10 substantially close to the window frame, while permitting its movement for adjustment in the manner indicated.

15 Referring to Fig. 4, the device 20 is similarly provided with two legs A and B, each having a longitudinal slot 21, and, on one side of this slot, a plurality of branches or recesses 22, each terminating in an enlarged recess 23, one portion of the enlargement extending upwardly and the other portion downwardly with reference to the recess 22. This construction admits of 20 the same device being used on either side of the window frame, making it at once a "right" and a "left" by merely turning it upside down. The screws 16 and 17 are spaced apart the distance between corresponding branches or recesses 22 in the 25 two legs A and B, and the operation of shifting the structure to make adjustments is as already described for Fig. 2.

Intermediate of the two legs A and B, a rod-supporting extension 25 is turned substantially at right angles to the base parts 30 A and B and then turned over at 26 and then back toward the base A and B as at 27, the part 27 constituting a stop for the end of the upper rod 13. The parts 25 and 40 26 are slotted as at 28 to receive the end of the rod 13, and the slot in the part 25 is cut out to form an enlarged recess 29, one part of the enlargement extending downward and the other part upward 45 with reference to the slot 28, the enlargement 29 thus providing a firm seat for the rod 13 when the device is used on either side of the window frame.

The lower rod 30 will ordinarily be held 50 by a fixed and non-adjustable holding device as 32, secured, as by screws, upon the window frame. It is usually desirable to have the lower end of the curtain maintained close to the lower horizontal part of 55 the window frame.

It is difficult to make curtains from the materials usually employed of such exact length as to fit tightly between two fixed rods. With the present device, the curtain 60 can be drawn and maintained taut regard-

less of the variations in length ordinarily found to exist. Furthermore, when these curtains are washed they usually shrink quite considerably, which shrinkage can be readily overcome, in effect, by the simple adjustment of the upper rod-holding members 10 or 20, as the case may be. I have found, too, that a notable advantage can be secured by putting the curtains back on the rods in their wet condition after being washed, 70 and, by means of the adjustable feature described, drawing them taut and leaving them to dry in that condition, thus avoiding much additional and laborious work. By this construction, too, the curtain may be 75 readily removed and replaced as desired.

The device can be formed by stamping processes well understood.

I claim:

1. A curtain fixture comprising a relatively long and narrow plate-like base having intermediate its ends a support for a curtain rod, said support being carried by said base, each end portion of the base having a longitudinal slot therein provided with a plurality of branches extending laterally therefrom, each of said slots and the branches thereof being respectively adapted to accommodate a screw-like holding element, substantially as described. 90

2. A curtain rod support comprising a base and a rod-supporting element carried thereby, said rod-supporting element having an opening on one side thereof to accommodate a curtain rod and being closed on the opposite side thereof to prevent said rod from projecting through said support, said base having a main longitudinal slot and branching slots extending therefrom on one side thereof, each branch slot terminating in an enlarged opening having a part thereof extending beyond said branch slot in each of the general directions of said main slot to form a seat for a screw-like holding element when the device is applied 100 with either end up, substantially as described. 105

3. A curtain fixture comprising a relatively long and narrow base adapted to rest vertically against a window frame part, an outwardly projecting support for the end of a horizontally disposed curtain rod carried by said base, said base having a main longitudinal slot normally vertically disposed and a plurality of lateral branch locking slots extending on one side of said main slot for accommodating the shank of a holding screw or the like in the window frame part, substantially as set forth. 110 115
